UNITED STATES PATENT OFFICE.

LOUIS FREEMAN, OF MONTREAL, QUEBEC, CANADA.

SKATING-OVERSHOE.

1,160,159.

Specification of Letters Patent. Patented Nov. 16, 1915.

Application filed December 1, 1913. Serial No. 804,062.

To all whom it may concern:

Be it known that I, LOUIS FREEMAN, a subject of the King of Great Britain, and resident of the city of Montreal, in the Province 5 of Quebec and Dominion of Canada, have invented certain new and useful Improvements in Skating-Overshoes, of which the following is a full, clear, and exact description.

10 This invention relates to an overshoe which can be worn over skating boots having attached ice skates, and the object is attained by providing an overshoe having a longitudinal slit in the center of the sole, as 15 illustrated in the accompanying drawings, in which:—

Figure 1 is a side elevation of the overshoe for the left foot. Fig. 2 is a rear elevation of the overshoe open. Fig. 3 is a 20 bottom plan view of the sole and heel.

Referring more particularly to the drawings, A designates the sole which is pierced by a slit or opening B, commencing at a point approximately one-quarter of an inch 25 from the toe and running in a straight line from the center of the toe to the center of the heel C at the back. This slit B is enlarged or widened at the front end, as shown at B' for the reception of the first 30 pillar of the skate. The sole is reinforced around this opening, as shown at B''. This reinforcement may if desired be extended the entire length of the slit.

At the back of the heel, the opening B 35 runs horizontally a short distance toward the inner side of the overshoe, thus separating the heel and upper, as clearly shown in Fig. 2, for a short distance. The outer portion D of the upper terminates approximately at the center of the back in line with 40 the slit B, while the inner portion E is provided with a flap F adapted to overlie the rear part of the outer upper D, as clearly shown in Fig. 1, and be attached thereto 45 by means of any suitable fastening devices G.

It will be noted that in making the overshoes, no provision is made in the slit B for any of the skate pillars except at the toe. This is because the pillars differ in size and 50 position in nearly all makes of skates. The purchaser of the overshoe can easily enlarge the slit B to suit his skates, or the adjustment can be made by the vendor when the overshoes are sold.

55 The application of the device is extremely simple. The fastenings G are released and

the overshoe opened, as shown in Fig. 2. It is then pulled over the toe of the skating boot, the split sole opening so as to pass the pillars of the skate. When the overshoe is 60 in place, the flap F is folded over the outer side D of the upper and secured by the fastenings G. This closes the slit B and forms a complete covering over the skating boot.

The overshoe may be made of any suitable materials and provided with any suitable kind of warm lining.

Having thus described my invention, what I claim is:—

1. An overshoe having a sole provided 70 with a slit piercing said sole and extending longitudinally thereof from the heel end to adjacent the toe end thereof, and an upper constructed and arranged to open up the back of the overshoe from the heel end of 75 the said slit.

2. An overshoe having a sole provided with a slit piercing said sole and extending longitudinally thereof from the heel end to adjacent the toe end thereof and being of 80 sufficient length to receive the pillars of a skate, and an upper constructed and arranged to open up the back of the overshoe from the heel end of said slit.

3. An overshoe having a sole provided 85 with a slit piercing said sole and extending longitudinally thereof from the heel end to adjacent the toe end thereof and being of 90 sufficient length to receive the pillars of a skate, an upper constructed and arranged to open up the back of the overshoe from the heel end of said slit, and a flap extending 95 from the inner side of the upper over the outer side thereof to form a closure for the opening in the upper at the back of the overshoe.

4. An overshoe for use with skating boots having a sole provided with a slit piercing said sole and extending at one end to the edge of the sole, said slit being adapted to 100 receive the pillars of a skate, and an upper having a closure opening extending upwardly from the end of the slit at the edge of the sole.

5. An overshoe for use with skating boots 105 having a sole provided with a slit piercing said sole and extending at one end to the edge of the sole, said slit having an enlargement adapted to receive one of the pillars of a skate, and an upper having a closure opening 110 extending upwardly from the end of the slit at the edge of the sole.

6. An overshoe for use with skating boots having a sole provided with a slit piercing said sole and extending at one end to the edge of the sole, said slit having an enlargement adapted to receive one of the pillars of a skate, an upper having a closure opening extending upwardly from the end of the slit at the edge of the sole, a flap forming a continuation of the upper at one side of the closure opening and adapted to

overlap the upper at the other side of said opening and coöoperating fastening means on the flap and upper.

In witness whereof I have hereunto set my hand in the presence of two witnesses. 15

LOUIS FREEMAN.
